CLAIM

I claim the ornamental design for subterranean injection rod tip, as shown and described.

DESCRIPTION

FIG. 1 is a perspective view of the subterranean injection rod tip showing my new design.

FIG. 2 is an enlargement view of FIG. 1 taken at the encirclement area of FIG. 1.

FIG. 3 is a side elevation view thereof the opposite side being a mirror image thereof.

FIG. 4 is a side elevation view thereof rotated 90 degrees of the previous view; the opposite side is a mirror image thereof; and,

FIG. 5 is a bottom plan view thereof.

The dot dash lines show portions of the subterranean injection rod tip that form no part of the claimed design. The broken lines in FIGS. 1-4 are for the purpose of depicting the boundary lines of the enlarged view and form no part of the claimed design. None of the broken lines form any part of the claimed design.

The subterranean injection rod tip is shown with a symbolic break in its length. The appearance of any portion of the article between the break lines forms no part of the claimed design.

1 Claim, 2 Drawing Sheets---
